(57) **CLAIM**

We claim the ornamental design for a built-in type speaker for electronic white board, as shown and described.

DESCRIPTION

FIG. 1 is a front perspective view of a built-in type speaker for electronic white board of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken line showing of built-in type speaker for electronic white board is included for the purpose of illustrating environment and forms no part of the claimed design. Additionally, the unevenly broken lines in the drawings define the limits of the claimed design.
